(57) **CLAIM**

The ornamental design for a belt alignment tool, as shown and described.

DESCRIPTION

FIG. 1 is a perspective view of a belt alignment tool in accordance with the present invention;

FIG. 2 is another perspective view of the belt alignment tool of FIG. 1 from a different direction;

FIG. 3 is a front view of the belt alignment tool of FIGS. 1 and 2;

FIG. 4 is a rear view of the belt alignment tool of FIGS. 1-3;

FIG. 5 is a first end view of the belt alignment tool of FIGS. 1-4;

FIG. 6 is a second end view of the belt alignment tool of FIGS. 1-5;

FIG. 7 is top view of the belt alignment tool of FIGS. 1-6; and,

FIG. 8 is bottom view of the belt alignment tool of FIGS. 1-7.

The broken line portions illustrate unclaimed elements that form no part of the claimed design.
